LASTING MACHINE

Fred C. Eastman, Marblehead, Mass., assignor to
United Shoe Machinery Corporation, Flemington, N. J., a corporation of New Jersey

Application October 28, 1941, Serial No. 416,829

43 Claims. (Cl. 12—14)

This invention relates to lasting machines, and is herein illustrated as applied to a machine which, except as hereinafter noted, is generally of the same construction as disclosed in United States Letters Patent No. 2,160,846, granted on June 6, 1939, on an application of mine and A. F. Pym's. That machine is a power-operated machine especially designed for use in lasting the toes of welt shoes. It is to be understood, however, that the invention is not limited to machine organizations of that particular character or to machines for lasting shoes of that particular kind.

An object of the invention is to provide, in combination with toe-lasting wipers, improved means for controlling the upper in such manner that it will be lasted tightly over the last and over an insole on the last and will be free from any wrinkles such as would be visible in the finished shoe. To this and other ends, the machine herein shown includes a member, hereinafter referred to as a retarder, which clamps the marginal portion of the upper on the wipers and cooperates with the latter to apply a pull to the upper while spreading its marginal portion outwardly to prevent any prominent wrinkles from forming in the course of the lasting operation. As herein illustrated, this retarder and the means provided for controlling it are substituted for the grippers and their operating mechanisms used for pulling and controlling the toe end of the upper in accordance with the disclosure of the above-mentioned Letters Patent. As one of its features, the invention provides novel means for so controlling the retarder as to vary its pressure on the upper in the lasting operation. In the construction shown the retarder is pressed on the upper by a spring as the wipers wipe it first heightwise of the last and then inwardly over the insole, and combined with this spring is frictionally acting means which supplements the force of the spring to increase the pressure of the retarder on the upper in the wiping of the upper heightwise of the last and then partially counteracts the force of the spring to reduce the pressure and thus avoid any danger of displacing the margin of the insole as the upper is wiped inwardly. Preferably, as illustrated, the upper is substantially released from the pressure of the retarder before the wipers complete their inward

movements to press its margin against a lip on the insole. As another of its features, the invention provides means for adjustably varying the time of such release, or the length of time that the retarder is effective on the upper. An advantageous characteristic of the construction shown, moreover, is that without such adjustment the control of the retarder varies in accordance with the thickness of the upper materials, so that on thick materials the retarder is effective longer than on thin materials.

In the illustrated embodiment of the invention the retarder is a substantially U-shaped member for controlling the upper at the end and the sides of the toe, this member being supported by the ends of its arms, in a location comparatively remote from the end of the toe, for swinging movements heightwise of the last, and it is pressed on the upper and controlled in the manner above described by a member which is moved heightwise of the last into engagement with it at the end of the toe. The retarder is, moreover, initially inclined heightwise of the last relatively to the wipers and becomes effective on the upper first at the end of the toe, thereafter swinging toward parallel relation to the wipers as the latter are moved heightwise of the last. In order to advance the time when the retarder becomes effective to press the upper on the wipers at the sides of the toe as the upper is wiped heightwise of the last by the wipers and to increase its effectiveness in those locations, the ends of its arms are supported by means which moves them heightwise of the last toward the wipers in response to frictional drag of the upper on the portion of the retarder at the end of the toe. Further novel features of the invention are to be recognized in the organization thus provided. In accordance with still another feature, the retarder is supported on an insole-engaging device with which the machine is provided for positioning the shoe and which is detachable to permit different devices to be used in operating on shoes of different styles or sizes, so that the retarder may be detached with this device and replaced by another retarder of the appropriate shape along with another such insole-engaging device.

The above and other features of the invention, including various novel details of construction and combinations of parts, will now be more

particularly described with reference to the accompanying drawings and thereafter pointed out in the claims.

In the drawings,

Fig. 1 is a view in right-hand side elevation of the upper portion of a machine in which the invention is embodied;

Fig. 2 is a view in rear elevation of a portion of the structure shown in Fig. 1;

Fig. 3 is a view in front elevation of a portion of the structure shown in Fig. 1;

Fig. 4 is a view partly in right-hand side elevation and partly in vertical section, showing mechanism provided for purposes of the present invention in its relation to other parts of the machine prior to the toe-lasting operation on a shoe;

Fig. 5 is mainly a plan view showing the wipers, the retarder and parts associated therewith as they appear when positioned as in Fig. 4, certain parts being shown in section;

Figs. 6, 7 and 8 are views of a portion of the structure shown in Fig. 4, showing the parts as they appear at different times in the lasting operation; and

Fig. 9 is a cam chart illustrating the time relation between the control of the retarder and the movements of the wipers.

As hereinabove suggested, the invention is illustrated as embodied in a machine constructed substantially as disclosed in the previously mentioned Letters Patent, except that the upper-pulling grippers and their operating mechanisms have been dispensed with and certain minor mechanical changes, which it is unnecessary to describe in detail, also have been made in order properly to control certain parts which were heretofore controlled by the gripper-operating means. The machine is provided with wipers 2 which, as heretofore, are advanced and closed to embrace the upper about the toe end of the last and are swung upwardly to wipe the upper heightwise of the last, after which they are further advanced and closed to wipe the marginal portion of the upper inwardly over the feather of a welt shoe insole on the last and against a lip on the insole. The lip is supported against the inward pressure of the wipers around the end and along the sides of the toe by a member 4 which also serves as a holdown member in engagements with the bottom face of the insole and determines the position of the last and shoe heightwise as well as lengthwise and laterally in the lasting operation. This member is mounted on a support 6 from which it is readily detachable to permit differently shaped members to be used in operating on shoes of different styles or sizes. The means for positioning and retaining the member 4 on its support 6 and for releasing it to permit it to be detached from the support differs somewhat from the disclosure of the above-mentioned Letters Patent. For this purpose the support 6 is provided with two pairs of segmental lugs 8 (Fig. 5) which extend downwardly into holes 10 in the member 4 and thus prevent movement of this member in any direction lengthwise or widthwise of the shoe. The member 4 is detachably held in the position determined by the lugs 8 by latch mechanism comprising a slide 12 movable in directions lengthwise of the shoe in a T-slot formed in the support 6 and provided with fingers 14 which extend downwardly between the lugs 8, these fingers being so formed as to project under portions of the

member 4 in recesses formed in this member, as illustrated in Fig. 4. The slide 12 is provided with a knob 16 by means of which it may be moved forwardly to release the member 4 against the resistance of a spring 18 which is mounted in a recess in the knob and is held in place by a screw 20 threaded in the support 6. After a shoe has been presented by the operator in the position determined by the member 4 it is clamped against this member by a toe rest 22 which is moved upward shortly after the starting of the power operation of the machine. The shoe is further controlled in the lasting operation by a heel rest 24 (Fig. 1) which is moved rearwardly into engagement with its heel end.

For purposes of this invention the machine is provided with a member 26, herein termed a retarder, by means of which the marginal portion of the upper is clamped on the wipers, so that the wipers and the retarder cooperate to apply a pull to the upper to assist in lasting it tightly over the toe end of the last and the edge of the insole. Additionally the retarder serves, by spreading the margin of the upper outwardly over the wipers, to control the margin in such manner as to prevent in the lasting operation the formation of any wrinkles which would be visible in the finished shoe. The retarder 26 in the construction herein shown is a substantially U-shaped member formed of substantially rigid wire and is supported on the detachable hold-down member 4, so that this member and the retarder may be detached as a unit to permit the substitution of a differently shaped member and a corresponding retarder for use on shoes of a different style or size. The retarder is arranged to clamp the upper on the wipers around the end and along the sides of the toe and has the end portions of its forwardly extending arms offset somewhat upwardly heightwise of the shoe relatively to the portions of the arms which clamp the upper on the wipers at the sides of the toe. The ends of the arms are bent inwardly and extend through holes provided in the two arms of a U-shaped holder 28, the ends of the arms of this holder being pivotally mounted on studs 29 fast on upwardly extending arms of a U-shaped bracket 30 which is secured to the lower face of a shelf extending forwardly from the holdown member 4. The upwardly extending arms of the bracket 30 have outwardly extending lips 32 arranged to overlie the portions of the retarder which are adjacent thereto. It will thus be seen that the retarder 26 is mounted on the holder 28 for swinging movements heightwise of the shoe relatively to the holdown member 4, and that the holder 28 also may swing more or less heightwise of the shoe on the bracket 30, carrying with it the ends of the arms of the retarder. The function of the means thus provided for supporting the retarder on the member 4 will be more particularly hereinafter explained.

The retarder 26 is pressed down on the upper and is controlled in the lasting operation by mechanism shown particularly in Fig. 4. This mechanism includes a bar 34 which is pivotally supported substantially midway between its opposite ends on an arm 35 mounted to swing about a rockshaft 38 supported in bearings on a head casting 40 (Fig. 1) on the frame of the machine. By swinging movements of the arm 35 the bar 34 is moved downwardly into engagement with the retarder 26 at the end of the toe to press it on the upper and is later moved upwardly away

from the retarder. In these movements the bar 34 is further guided and controlled by an arm 42 which is pivotally connected to its upper end and is mounted for swinging movements on a lug 44 formed on a plate 46 (Fig. 1) which is secured to the head casting 40. Integral with the arm 36 is another arm 48 adjustably connected by a spindle 50 to an arm 52 which is integral with the upper part 54 of a two-part clamp 56 embracing a friction ring 58 on the rockshaft 38, the ring being held in fixed relation to the rockshaft by a pin 60 threaded in the rockshaft and extending through a hole in the ring. The clamp 56 has a lower part 62 connected to the upper part 54 by a link 64. Pivotally mounted at one end on the upper part 54 is a lever 66 connected midway between its opposite ends to the lower part 62 by a link 68. The other end of the lever 66 is connected to the lower end of a spring 70 the upper end of which is connected to one arm of a lever 72 (Fig. 2) pivotally mounted at 74 on the plate 46. By swinging this lever the tension of the spring may be varied, the lever being provided with a spring-controlled pin 76 arranged to enter any one of a plurality of holes 78 in the plate 46 to retain the lever in adjusted position. It will be evident that the spring 70 tends by its action on the lever 66 and the link 68 to tighten the two-part clamp 56 on the friction ring 58 and also to turn the clamp about the axis of the rockshaft 38 and thereby to move the bar 34 in a downward direction. Initially, however, such turning of the clamp is prevented by engagement of the pin 60 with a shoulder 80 on the lower part 62 of the clamp, as illustrated in Fig. 4, the bar 34 being held by the pin in an upraised position away from the retarder 26. It is only, therefore, in response to turning movement of the rockshaft 38 in a counterclockwise direction, as the parts are viewed in Fig. 4, that the spring 70 is permitted to impart downward movement to the bar 34. The rockshaft is automatically controlled in the power operation of the machine by a cam 82 (Fig. 1) the periphery of which engages a roll 84 mounted on one arm of a bell-crank lever 86 the other arm of which is connected by a link 88 to an arm 90 fast on the rockshaft 38. A spring 92 connected to the bell-crank lever 86 holds the roll 84 at all times in engagement with the cam and serves when permitted by the cam to turn the rockshaft 38 in the above-mentioned counterclockwise direction.

The above-described downward movement of the bar 34 into position to control the retarder in the lasting operation takes place prior to the upwiping action of the wipers 2 on the toe end of the upper. After the wipers in their upward movement have arrived in position to clamp the upper against the retarder controlled by the bar 34, they cooperate with the retarder as they are moved farther upwardly to apply a pull to the upper as it is being wiped heightwise of the last. In this operation the bar 34 is lifted by the pressure of the retarder on its lower end, causing the clamp 56 to turn about the friction ring 58 against the resistance of the spring 70, this movement of the clamp being permitted by a slot 94 provided therein through which the pin 60 extends. It will be evident that in this operation the friction between the clamp and the ring 58 supplements the force of the spring 70 in resisting the upward movement of the bar 34 and therefore increases the force with which the retarder is pressed on the upper. When the wipers

wipe the margin of the upper inwardly over the insole the retarder is so controlled as to apply less pressure to the upper than during the greater portion of the upwiping operation, thus avoiding any danger that the force applied to the upper by the wipers will displace the margin of the insole. For this purpose, when the wipers have nearly arrived at the limit of their upwiping movement, the cam 82 begins to turn the rockshaft 38 in a clockwise direction (Fig. 4), causing the ring 58 by frictional engagement with the clamp 56 partially to counteract the force of the spring 70. The reduced pressure of the retarder on the upper is thus continued as the wipers begin to wipe the margin of the upper inwardly. Before the wipers have completed their inward wiping movements the pin 60 arrives in position again to engage the shoulder 80 of the clamp 56 and then acts positively on the clamp to lift the bar 34 and release the margin of the upper from the pressure of the retarder. This permits the margin of the upper to spring upwardly as the wipers complete their inward movements, so that the margin is in better position to be trimmed at a later stage in the manufacture of the shoe than if it were held outspread over the wipers until the end of their inward movements. Continued turning of the rockshaft 38 raises the bar 34 to its initial position.

Reference has been made to the fact that the arm 48 connected to the bar 34 is adjustably connected by the spindle 50 to the arm 52 of the clamp 56. This spindle is swiveled in a trunnion block 96 pivotally mounted on the arm 48 and is threaded in a trunnion block 98 pivotally mounted on the arm 52. Accordingly, turning of the spindle by means of a hand wheel 100 fast thereon serves to swing the arms 48 and 36 and thus to lower or raise the bar 34 while the clamp 56 is stationary. The purpose and effect of such an adjustment is to vary the length of time in the lasting operation that the bar 34 is effective to press the retarder on the upper. If the bar is adjusted, for example, in a downward direction, it will move the retarder to a lower position in response to the first turning movement of the rockshaft 38 and, accordingly, the retarder will be pressed on the upper a greater length of time in the upwiping operation. The bar 34, therefore, will be lifted a greater distance in the upwiping operation and the shoulder 80 of the clamp 56 will be carried farther away from the pin 60 than if such an adjustment had not been made. By reason of the greater space thus provided between the shoulder and the pin and the consequent provision for more lost motion, the rockshaft 38 will thereafter have to move farther in a clockwise direction before the pin meets the shoulder, and, accordingly, the lifting of the bar 34 to release the pressure on the upper will take place later in the course of the inward wiping movements of the wipers than if the adjustment had not been made. Conversely, an adjustment of the bar 34 in an upward direction will serve to reduce the length of time that the retarder is pressed on the upper in both the upwiping and overwiping operations. It will be further evident that, the adjustment of the bar remaining the same, the retarder will be pressed on the upper longer in both those operations the greater the thickness of the upper materials.

The manner of operation of the machine, in so far as it is of interest with reference to the present invention, will now be briefly summarized and the action of certain parts will be described in

greater detail. Before a shoe is presented to the machine the retarder 26 normally rests in an inclined position under the influence of gravity on the studs 29 which are extended for that purpose, the holder 28 being swung upwardly as far as permitted by the outwardly extending lips 32 of the arms of the bracket 30. The shoe is presented by the operator in the position determined by engagement of the member 4 with the bottom face and the lip of the insole with the marginal portion of the upper around the toe inclined outwardly from the last so that it will later overlie the toe wipers 2. As the shoe is thus presented, engagement of the upper with the retarder may lift the latter slightly, swinging it upwardly about its connection with the holder 28, as indicated in Fig. 4. Shortly after the starting of the power operation of the machine the toe rest 22 is moved upwardly to clamp the shoe against the member 4, and at a predetermined time also the heel rest 24 is moved into supporting engagement with the heel end of the shoe. Early in the cycle of operations of the machine the wipers 2 are advanced and closed about the toe end of the shoe into positions to render them properly effective in the wiping of the upper heightwise of the toe and are swung upwardly to perform this operation on the upper. As indicated on the cam chart (Fig. 9) this upwiping operation takes place between 95° and 135° of the cycle. Prior to the beginning of the upwiping operation, however, the rockshaft 38 is turned in a counterclockwise direction (Fig. 4) to permit the spring 70 to turn the clamp 56 also in that direction and thereby to impart downward movement to the bar 34 which controls the retarder 26 in the lasting operation. The frictional action of the ring 58 on the clamp also assists in thus turning the clamp. This downward movement of the bar 34 takes place between 30° and 80° of the cycle and therefore terminates before the upwiping action of the wipers begins. Near the end of its movement the bar engages the retarder and depresses it, for example, to the position illustrated in Fig. 6, the limit of the downward movement of the bar and of the retarder being variable as determined by adjustment of the spindle 50, as hereinbefore explained. The retarder is, therefore, held by the bar in position for the portion thereof which is located at the end of the toe to clamp the margin of the upper outspread on the wipers when the latter in their upwiping movement arrive in the position illustrated, for example, in Fig. 6. Thereafter, as the wipers are moved farther upwardly, they cooperate with the retarder to apply a pull to the upper in a direction heightwise of the last, the retarder being swung upwardly about its connection with the holder 28 to a position more nearly parallel to the top faces of the wipers. In this operation the bar 34 is forced upwardly by the retarder and acts to turn the clamp 56 in a clockwise direction (Fig. 4) about the friction ring 58 against the resistance of the spring 70, the friction between the clamp and the ring serving in addition to the spring 70 to resist this movement and therefore serving to increase the pressure of the retarder on the upper. In the upwiping operation the marginal portion of the toe end of the upper slips more or less inwardly toward the last between the wipers and the retarder and thereby exerts a frictional drag on the retarder at the end of the toe with a tendency to move it in a heelward direction. As a result of this action of the upper on the retarder the inclined holder 28 is swung downwardly about the

studs 29 and thereby carries the portions of the retarder at the sides of the toe downwardly toward the wipers while assisting in bringing them into positions substantially parallel to the top faces of the wipers, as illustrated in Fig. 7. In this manner the retarder is rendered effective to clamp the upper on the wipers at the sides of the toe toward the end of the upwiping operation. In the final portion of the upwiping operation the retarder may be lifted bodily by the wipers until its arms engage the lips 32 of the bracket 30, as illustrated in Fig. 8.

When the wipers have arrived substantially in the position illustrated in Fig. 7, the rockshaft 38 begins to turn reversely in a clockwise direction (Fig. 4). As illustrated by the cam chart (Fig. 9) this movement of the rockshaft begins at 130° of the cycle, whereas the upwiping movement of the wipers terminates at 135° of the cycle. During the final portion of the upwiping operation, therefore, the turning of the rockshaft causes the ring 58 to act frictionally on the clamp 56 with a tendency to turn it against the resistance of the spring 70, thus partially counteracting the force of the spring and reducing the pressure with which the retarder is held against the upper by the bar 34. This reduction of pressure continues as the wipers begin, at 135° of the cycle, to wipe the margin of the upper inwardly in the manner illustrated in Fig. 8 until such time as the pin 60 again engages the shoulder 80 of the clamp 56. Thereafter, in response to further turning of the rockshaft, the bar 34 is lifted by the action of the pin 60 on the clamp, thereby releasing the upper from the pressure of the retarder. Fig. 8 illustrates the positions of the parts when the bar 34 thus starts to leave the retarder, but as herein before explained the time of such release of the pressure may be varied by turning the spindle 50. By reason of the reduction of the pressure on the margin of the upper near the end of the upwipe and at the beginning of the overwipe insurance is afforded against danger of displacement of the margin of the insole by the force of the wipers on the upper. By releasing the margin of the upper substantially from pressure before the completion of the overwiping operation the margin, as hereinbefore explained, is permitted to spring upwardly more or less as the wipers continue their inward movements, so as to assume a better position for a later upper-trimming operation than if it were clamped firmly against the top faces of the wipers until the completion of the overwiping operation. After the release of the pressure on the upper the bar 34 is moved upwardly to its initial position by continuing turning movement of the rockshaft 38. The remainder of the cycle of operations of the machine, as far as the wipers are concerned, is substantially as disclosed in the previously mentioned Letters Patent except that, as indicated by the cam chart, the wipers receive a short downward movement to bring greater pressure to bear on the overwiped margin of the upper just before the machine comes to a stop at 175° of the cycle to permit the operator to begin the toe-wiring operation, instead of being moved upward a short distance at that time as in the earlier construction. When the machine is again started the wipers are lifted to permit the binder wire to be drawn properly inward under them in a manner similar to the disclosure of the above-mentioned Letters Patent.

Having described the invention, what I claim

as new and desire to secure by Letters Patent of the United States is:

1. In a lasting machine, wipers for wiping the toe-end portion of an upper on a last into lasted position, a retarder for clamping the upper on the wipers in the wiping operation, mechanism for controlling said retarder, a spring arranged to act through said mechanism to press the retarder on the upper, and means arranged to act directly on said mechanism to vary the pressure of the retarder on the upper in the wiping operation while the pressure is maintained by said spring.

2. In a lasting machine, wipers for wiping the toe-end portion of an upper on a last into lasted position, a retarder for clamping the upper on the wipers in the wiping operation, mechanism for controlling said retarder, a spring arranged to act through said mechanism to press the retarder on the upper, and automatic means arranged to act directly on said mechanism first to increase the pressure of the retarder on the upper and thereafter to reduce said pressure in the course of the wiping operation while the pressure is maintained by said spring.

3. In a lasting machine, wipers for wiping the toe-end portion of an upper on a last heightwise of the last and then inwardly over an insole on the last, a retarder for clamping the upper on the wipers, mechanism for controlling said retarder, a spring arranged to act through said mechanism to press the retarder on the upper as the upper is wiped heightwise of the last and inwardly by the wipers, and power-operated means arranged to act directly on said mechanism to reduce the pressure of the retarder on the upper when the wipers have substantially completed the wiping of the upper heightwise of the last and to continue such reduction of pressure as the wipers begin to wipe the upper inwardly.

4. In a lasting machine, wipers for wiping the toe-end portion of an upper on a last heightwise of the last and then inwardly over an insole on the last, a retarder for clamping the upper on the wipers in the wiping operation, a device for controlling said retarder, a spring arranged to act through said device to press the retarder on the upper, and mechanism arranged to act directly on said device first to supplement the force of said spring and thereby to increase the pressure of the retarder on the upper in the wiping of the upper heightwise of the last and thereafter partially to counteract the force of the spring and thereby to reduce said pressure while the pressure is still maintained by the spring.

5. In a lasting machine, wipers for wiping the toe-end portion of an upper on a last into lasted position, a retarder for clamping the upper on the wipers in the wiping operation, a device for controlling said retarder, a spring arranged to act through said device to press the retarder on the upper, and means arranged to act frictionally on said device to vary the pressure of the retarder on the upper in the wiping operation while the pressure is maintained by said spring.

6. In a lasting machine, wipers for wiping the toe-end portion of an upper on a last heightwise of the last and then inwardly over an insole on the last, a retarder for clamping the upper on the wipers in the wiping operation, a device for controlling said retarder, a spring arranged to act through said device to press the retarder on the upper, and means arranged to act frictionally on said device to increase the pressure of the retarder on the upper in the wiping of the upper heightwise of the last and to reduce said pressure

preparatory to the wiping of the upper inwardly while the pressure is still maintained by said spring.

5 7. In a lasting machine, wipers for wiping the toe-end portion of an upper on a last heightwise of the last and then inwardly over an insole on the last, a retarder for clamping the upper on the wipers in the wiping operation, a device for controlling said retarder, a spring arranged to act through said device to press the retarder on the upper, and power-operated means arranged to act frictionally on said device and movable partially to counteract the force of said spring on the retarder as the upper is wiped inwardly by the wipers.

10 8. In a lasting machine, wipers for wiping the toe-end portion of an upper on a last into lasted position, a retarder for clamping the upper on the wipers in the wiping operation, a spring for pressing said retarder on the upper, and mechanism including members relatively movable in frictional engagement with each other in the wiping operation to vary by such frictional engagement the pressure of the retarder on the upper while the pressure is maintained by said spring.

15 9. In a lasting machine, wipers for wiping the toe-end portion of an upper on a last heightwise of the last and then inwardly over an insole on the last, a retarder for clamping the upper on the wipers in the wiping operation, a spring for pressing said retarder on the upper, and mechanism including members relatively movable in frictional engagement with each other in predetermined time relation to the operation of the wipers first to increase and thereafter to reduce by their frictional engagement the pressure of the retarder on the upper while the pressure is maintained by said spring.

20 10. In a lasting machine, wipers for wiping the toe-end portion of an upper on a last into lasted position, a retarder for clamping the upper on the wipers in the wiping operation, a device mounted for turning movement to press said retarder on the upper, a spring for thus turning said device, and a member also mounted for turning movement and arranged to act by frictional contact with said device to vary the pressure of the retarder on the upper in the course of the wiping operation.

25 11. In a lasting machine, wipers for wiping the toe-end portion of an upper on a last heightwise of the last and then inwardly over an insole on the last, a retarder for clamping the upper on the wipers in the wiping operation, a device mounted for turning movement to press said retarder on the upper, a spring for thus turning said device, a member also mounted for turning movement and arranged to act frictionally on said device, and power-operated means for turning said member in predetermined time relation to the operation of the wipers to cause it by frictional contact with said device to reduce the pressure of the retarder on the upper while the pressure is maintained by said spring.

30 12. In a lasting machine, wipers for wiping the toe-end portion of an upper on a last into lasted position, a retarder for clamping the upper on the wipers in the wiping operation, a friction member mounted for turning movement, a clamp applied to said friction member and also mounted for turning movement to press the retarder on the upper, a spring for turning said clamp thus to press the retarder on the upper and for also holding the clamp tightly applied to said friction

member, and means for turning said member to cause it by its frictional contact with the clamp to vary the pressure of the retarder on the upper in the course of the wiping operation.

13. In a lasting machine, wipers for wiping the toe-end portion of an upper on a last into lasted position, a retarder for clamping the upper on the wipers in the wiping operation, a device movable to press the retarder on the upper, a spring for thus moving said device, and mechanism arranged to hold said device initially retracted against the resistance of the spring and movable to release it to the action of the spring, said mechanism including a member arranged for frictional contact with said device to increase by such contact the pressure of the retarder on the upper in the wiping operation.

14. In a lasting machine, wipers for wiping the toe-end portion of an upper on a last into lasted position, a retarder for clamping the upper on the wipers in the wiping operation, a device movable to press the retarder on the upper, a spring for thus moving said device, and mechanism arranged to hold said device initially retracted against the resistance of the spring and movable to release it to the action of the spring, said mechanism including a member movable in frictional contact with said device to reduce by such contact the pressure of the retarder on the upper in the course of the wiping operation while the pressure is maintained by the spring.

15. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved heightwise of the last and thereafter to control the upper as it is wiped inwardly by the wipers, a spring for pressing the retarder on the upper, and mechanism including members relatively movable in frictional engagement with each other in response to the movement of the wipers heightwise of the last to increase by such frictional engagement the pressure of the retarder on the upper.

16. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved heightwise of the last and thereafter to control the upper as it is wiped inwardly by the wipers, a spring for pressing the retarder on the upper, mechanism including members relatively movable in frictional engagement with each other in response to the movement of the wipers heightwise of the last to increase by such frictional engagement the pressure of the retarder on the upper, and means for effecting relative movement of said members partially to counteract the force of said spring and thereby to reduce the pressure of the retarder on the upper in the course of the lasting operation.

17. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved heightwise of the last and thereafter to control the upper as it is wiped inwardly by the wipers, a device for controlling said retarder, a spring arranged to act through said device to press the

retarder on the upper, a member arranged to act frictionally on said device in response to the movement of the wipers heightwise of the last to increase the pressure of the retarder on the upper, and means for moving said member in frictional engagement with said device partially to counteract the force of said spring on the retarder as the upper is wiped inwardly by the wipers.

18. In a lasting machine, wipers for wiping the toe-end portion of an upper on a last heightwise of the last and then inwardly over an insole on the last, a retarder for clamping the upper on the wipers as the upper is thus wiped heightwise of the last and inwardly over the insole, and automatic means for reducing the pressure of the retarder on the upper when the wipers have substantially completed the wiping of the upper heightwise of the last and for thereafter substantially releasing the upper from the pressure of the retarder after the wipers have begun but before they have completed the wiping of the upper inwardly.

19. In a lasting machine, wipers for wiping the toe-end portion of an upper on a last heightwise of the last and then inwardly over an insole on the last, a retarder for clamping the upper on the wipers as the upper is thus wiped heightwise of the last and inwardly over the insole, a device for controlling said retarder, a spring arranged to act through said device to press the retarder on the upper, means arranged to act frictionally on said device to reduce the pressure of the retarder on the upper when the wipers have substantially completed the wiping of the upper heightwise of the last and to continue such reduction of pressure as the wipers begin to wipe the upper inwardly, and additional means for substantially releasing the upper from the pressure of the retarder before the wipers have completed the wiping of the upper over the insole.

20. In a lasting machine, wipers for wiping the toe-end portion of an upper on a last heightwise of the last and for then wiping its margin inwardly over an insole on the last and against a lip on the insole, a retarder for clamping the marginal portion of the upper outspread on the wipers as the upper is thus wiped heightwise of the last and inwardly over the insole, and automatic means for reducing the pressure of the retarder on the upper when the wipers have substantially completed the wiping of the upper heightwise of the last and for thereafter substantially releasing the upper from the pressure of the retarder after the wipers have begun to wipe the upper inwardly but before they have pressed it against the lip of the insole.

21. In a lasting machine wipers for wiping the toe-end portion of an upper on a last heightwise of the last and for then wiping its margin inwardly over an insole on the last and against a lip on the insole, a retarder for clamping the marginal portion of the upper outspread on the wipers as the upper is thus wiped heightwise of the last and inwardly over the insole, a device mounted for turning movement to press the retarder on the upper, a spring for thus turning said device, a member also mounted for turning movement and arranged to act frictionally on said device to reduce the pressure of the retarder on the upper when the wipers have substantially completed the wiping of the upper heightwise of the last and to continue such reduction of pressure as the wipers begin to wipe the upper inwardly, and means arranged to turn with said

member and to act on said device to release the upper substantially from the pressure of the retarder before the wipers have pressed the upper against the lip of the insole.

22. In a lasting machine, wipers movable to wipe the marginal portion of the toe end of an upper inwardly over an insole on a last, a retarder for clamping the marginal portion of the upper on the wipers to control it in the wiping operation, and controlling means for pressing said retarder on the upper and for thereafter automatically releasing the upper substantially from the pressure of the retarder in predetermined time relation to the movement of the wipers, said controlling means being adjustable to vary relatively to the movement of the wipers the time of such release of the upper.

23. In a lasting machine, wipers movable to wipe the marginal portion of the toe end of an upper inwardly over an insole on a last, a retarder for clamping the marginal portion of the upper on the wipers to control it in the wiping operation, and controlling means for pressing said retarder on the upper and for thereafter automatically releasing the upper substantially from the pressure of the retarder in predetermined time relation to the movement of the wipers, said controlling means including lost-motion mechanism for varying in accordance with the amount of lost motion the time of such release of the upper relatively to the movement of the wipers.

24. In a lasting machine, wipers for wiping the toe-end portion of an upper on a last heightwise of the last and then inwardly over an insole on the last, a retarder for clamping the marginal portion of the upper on the wipers as the upper is thus wiped heightwise of the last and inwardly by the wipers, and controlling means for pressing said retarder on the upper and for thereafter automatically releasing the upper substantially from the pressure of the retarder before the wipers have completed the wiping of the upper inwardly over the insole, said controlling means being adjustable to vary relatively to the operations of the wipers the time when the retarder becomes effective to press the upper on the wipers and the time of such release of the upper from pressure.

25. In a lasting machine, wipers for wiping the toe-end portion of an upper on a last heightwise of the last and then inwardly over an insole on the last, a retarder for clamping the marginal portion of the upper on the wipers as the upper is thus wiped heightwise of the last and inwardly by the wipers, and controlling means for pressing said retarder on the upper and for thereafter automatically releasing the upper substantially from the pressure of the retarder before the wipers have completed the wiping of the upper inwardly over the insole, said controlling means being adjustable to vary relatively to the wiping of the upper heightwise of the last the time when the retarder becomes effective to press the upper on the wipers and including mechanism for varying automatically the time of the release of the upper from pressure in accordance with variations in the time when the retarder thus becomes effective on the upper.

26. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved

heightwise of the last and thereafter to control the upper as it is wiped inwardly by the wipers, and controlling means for pressing said retarder on the upper and for thereafter automatically releasing the upper substantially from the pressure of the retarder before the wipers have completed the wiping of the upper inwardly over the insole, said controlling means being adjustable to advance or delay relatively to the movement of the wipers heightwise of the last the time when the retarder becomes effective to press the upper on the wipers and including automatic mechanism for correspondingly delaying and advancing respectively as a result of such adjustment the time of the release of the upper from the pressure of the retarder.

27. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved heightwise of the last and thereafter to control the upper as it is wiped inwardly by the wipers, a member movable heightwise of the last to press the retarder on the upper and reversely movable thereafter heightwise of the last to release the upper substantially from the pressure of the retarder, and operating means for thus moving said member, said member being adjustable heightwise of the last relatively to said operating means.

28. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved heightwise of the last and thereafter to control the upper as it is wiped inwardly by the wipers, a member movable heightwise of the last to press the retarder on the upper and reversely movable thereafter heightwise of the last to release the upper substantially from the pressure of the retarder, a controlling device mounted for turning movements thus to move said member in opposite directions heightwise of the last, a spring for turning said device in the direction to press the retarder on the upper, a power-operated member movable fixed distances in opposite directions to release said device to the action of the spring and to return it against the resistance of the spring respectively, and means for adjusting said first-named member in directions heightwise of the last relatively to said controlling device.

29. In a lasting machine, wipers movable to wipe the marginal portion of the toe end of an upper inwardly over an insole on a last, a retarder for clamping the marginal portion of the upper on the wipers to control it in the wiping operation, and controlling means for pressing said retarder on the upper and for thereafter releasing the upper substantially from the pressure of the retarder at a time relatively to the movement of the wipers automatically variable in accordance with the thickness of the upper materials.

30. In a lasting machine, toe-lasting wipers movable heightwise of a last and movable thereafter to wipe the marginal portion of an upper inwardly over an insole on the last, a retarder for clamping the upper on the wipers to apply a pull to the upper as the wipers are moved heightwise of the last and thereafter to control the upper as it is wiped inwardly by the wipers,

and controlling means for pressing said retarder on the upper at a time relatively to the movement of the wipers heightwise of the last automatically variable in accordance with the thickness of the upper materials, said controlling means including mechanism for thereafter automatically releasing the upper substantially from the pressure of the retarder at a time in the wiping of the upper inwardly over the insole variable in accordance with variations in the time when the retarder is thus pressed on the upper.

31. In a lasting machine, wipers for wiping the toe-end portion of an upper on a last into lasted position, a retarder for clamping the upper on the wipers in the wiping operation, means supporting said retarder, and additional means supported independently of the retarder and movable heightwise of the last into engagement with it to press it on the upper.

32. In a lasting machine, wipers for wiping the toe-end portion of an upper on a last into lasted position, a retarder arranged to clamp the upper on the wipers around the end and along the sides of the toe, means supporting said retarder by engaging it in a location spaced lengthwise of the last from the end of the toe, and mechanism including a member movable heightwise of the last into engagement with the portion of the retarder at the end of the toe to press the retarder on the upper.

33. In a lasting machine, wipers for wiping the toe-end portion of an upper on a last into lasted position, a substantially U-shaped retarder arranged to clamp the upper on the wipers around the end and along the sides of the toe, means supporting said retarder for swinging movements heightwise of the last by engaging it in a location spaced lengthwise of the last from the end of the toe, and mechanism including a member movable heightwise of the last into engagement with the portion of the retarder at the end of the toe to press the retarder on the upper.

34. In a lasting machine, wipers for wiping the toe-end portion of an upper on a last into lasted position, a retarder for clamping the upper on the wipers at the end and the sides of the toe in the wiping operation, and means for forcing portions of the retarder at the sides of the toe heightwise of the last toward the wipers to increase the pressure of those portions on the upper in response to frictional drag of the upper on the portion of the retarder at the end of the toe.

35. In a lasting machine, wipers for wiping the toe-end portion of an upper on a last into lasted position, a retarder for clamping the upper on the wipers at the end and the sides of the toe in the wiping operation, and a device supporting said retarder by engaging it in a location spaced lengthwise of the last from the end of the toe, said device being movable to force portions of the retarder at the sides of the toe heightwise of the last toward the wipers to increase the pressure of those portions on the upper in response to frictional drag of the upper on the portion of the retarder at the end of the toe.

36. In a lasting machine, wipers for wiping the toe-end portion of an upper on a last into lasted position, a retarder for clamping the upper on the wipers at the end and the sides of the toe in the wiping operation, and a device supporting said retarder by engaging it in a location spaced lengthwise of the last from the end of the toe, said device being mounted for swinging move-

ment heightwise of the last to increase the pressure of the portions of the retarder at the sides of the toe on the upper in response to frictional drag of the upper on the portion of the retarder at the end of the toe.

37. In a lasting machine, wipers for wiping the toe-end portion of an upper on a last into lasted position, a retarder for clamping the upper on the wipers at the end and the sides of the toe in the wiping operation, a device on which said retarder is pivotally mounted for swinging movement heightwise of the last in a location spaced lengthwise of the last from the end of the toe, and means for pressing the retarder on the upper at the end of the toe, said device being mounted for swinging movement heightwise of the last to increase the pressure of the portions of the retarder at the sides of the toe on the upper in response to frictional drag of the upper on the portion of the retarder at the end of the toe.

38. In a lasting machine, wipers for wiping the toe-end portion of an upper on the last heightwise of the last and then inwardly over an insole on the last, a retarder for clamping the marginal portion of the upper on the wipers as the upper is thus wiped heightwise of the last and inwardly by the wipers, said retarder being arranged to press the upper on the wipers first at the end of the toe in an inclined relation to the wipers and being mounted for swinging movement heightwise of the last toward parallel relation to the wipers for thereafter pressing the upper on the wipers also at the sides of the toe in the course of the wiping operation.

39. In a lasting machine, wipers for wiping the toe-end portion of an upper on a last heightwise of the last and then inwardly over an insole on the last, a substantially U-shaped retarder for clamping the marginal portion of the upper on the wipers as the upper is thus wiped heightwise of the last and inwardly by the wipers, means supporting said retarder by the ends of its arms for swinging movement heightwise of the last, and means for rendering the retarder effective on the upper first at the end of the toe in inclined relation to the wipers, the retarder being movable toward parallel relation to the wipers in the wiping of the upper heightwise of the last for pressing the upper on the wipers also at the sides of the toe.

40. In a lasting machine, toe-lasting wipers movable heightwise of a last and movable thereafter to wipe the marginal portion of an upper inwardly over an insole on the last, a substantially U-shaped retarder for clamping the marginal portion of the upper on the wipers to apply a pull to the upper as the wipers are moved heightwise of the last and thereafter to control the upper as it is wiped inwardly by the wipers, and means supporting said retarder by the ends of its arms for swinging movement heightwise of the last from an initial inclined relation to the wipers toward parallel relation thereto in response to the movement of the wipers heightwise of the last, said supporting means being movable to carry the ends of said arms heightwise of the last toward the wipers in the course of that movement of the wipers.

41. In a lasting machine, wipers for wiping the toe-end portion of the upper on a last into lasted relation to an insole on the last, a holdown device for engaging the toe end of the insole, a substantially U-shaped retarder supported by the ends of its arms on said holdown device for

clamping the upper on the wipers in the wiping operation, and a support from which said device and retarder are detachable as a unit to permit different holddown devices and corresponding retarders to be used in operating on shoes of different styles or sizes.

42. In a lasting machine, wipers for wiping the toe-end portion of an upper on a last into lasted relation to an insole on the last and for pressing the marginal portion of the upper against a lip on the insole, a member arranged to engage the toe end of the insole and to support said lip against the pressure of the wipers around the end and along the sides of the toe, a retarder supported on said member for clamping the upper on the wipers in the wiping operation, and a support from which said member and re-

tarder are detachable as a unit to permit different members and corresponding retarders to be used in operating on shoes of different styles or sizes.

5 43. In a lasting machine, wipers for wiping the toe-end portion of an upper on a last into lasted relation to an insole on the last, a hold-down device for engaging the toe end of the insole, a support from which said device is detachable to permit different devices to be used in operating on shoes of different styles or sizes, latch mechanism movable to release said device from its support, and a retarder for clamping the upper on the wipers in the wiping operation, 10 the retarder being supported on said holdown device for detachment with it.

FRED C. EASTMAN.
